UNITED STATES PATENT OFFICE

FRANK D. POWELL, OF CHICAGO, ILLINOIS, ASSIGNOR TO ACME CARD SYSTEM COMPANY, OF CHICAGO, ILLINOIS, A CORPORATION OF ILLINOIS

VISIBLE RECORD SYSTEM

Application filed January 3, 1930. Serial No. 418,234.

This invention relates to improvements in visible record systems, and refers more particularly to improvements in visible record systems of the type in which data-containing cards are removably mounted in overlapping relation on hangers, which hangers are preferably removably mounted in a frame.

Among the salient objects of the invention are to provide a visible record system of the type referred to in which a large number of cards may be removably held in one frame; to so mount the cards that they may overlap and expose a marginal edge; to provide hangers for the cards which will serve to securely hold them in the frame; to permit of the ready insertion and removal of the hangers with respect to the frame; to provide for the removable engagement of the cards with their hangers; to permit a plurality of cards to be mounted on a single hanger; to provide a construction wherein flat rectangular cards may be employed; to permit of ready access to any card, or cards in the series; to permit of the insertion of a card between other cards already in place and in general to provide a visible record system of the type referred to which can be economically manufactured and rapidly assembled.

A principal object of the present invention is to provide, in a system of the type referred to, means for quickly and conveniently mounting a card upon a hanger, the arrangement being such that the web of the frame and the main body portion of the hanger constitute a positive guide for inserting or threading a hinge attached to a card upon a hanger.

The frames upon which the cards are mounted usually comprise drawers of a filing cabinet, the drawers or frames being mounted one above the other in spaced relation for independent movement. Obviously, the number of drawers mountable in a cabinet of a given height will depend upon the depth of the drawers, or frames, which in turn is dependent upon the depth of the cards upon each frame.

Accordingly, another important object of

the present invention resides in the provision of removable card hangers constructed in such a manner as to permit of the insertion of a maximum number of removable hangers in a frame and yet permit the cards upon the hangers to occupy a minimum depth upon the frame. 55

The invention further resides in various features of construction and combinations of parts hereinafter disclosed. 60

In the drawings, Fig. 1 is a front elevational view partly in section of a frame and cards illustrating one application of my invention.

Fig. 2 is a sectional view taken on the line 65 2-2 of Fig. 1.

Fig. 3 is a perspective view of one of the card hangers.

Fig. 4 is a fragmentary detail perspective illustrating the means for mounting a card 70 upon a hanger.

Referring in detail to the drawings, 1 indicates a frame consisting of a web 2 having flanged edge portions 3 and 4 between which and the web the ends of the hangers 75 7 are inserted and held. The frame may be provided with similar flanges (not shown) on the opposite side of web 2 to permit cards and hangers to be mounted upon both faces of the web. The cards 5 are 80 hinged upon the hangers by means of hinges 6 formed of metal or other suitable material and are adapted to swing on these hinges as shown best in Fig. 4.

Each hanger may comprise a length of 85 resilient metal consisting of a main body portion 8 having return-bent ends 9 extending inwardly for a limited portion of the length of the hanger. The ends of these return-bent portions may be offset as shown at 10, 90 and preferably bent inwardly toward the main body portion 8 so that the ends of the return bends are parallel to the main body portion 8, as shown best at 11 in Fig. 3. In use, the ends 12 and 13 of the hanger are 95 inserted beneath the flanges 3 and 4 of the frame. This may be done by flexing the body portion 8 intermediate its length sufficiently to permit the ends to be inserted beneath the flanges. The hanger may then 100

be allowed to spring back into normal position. In normal position each hanger 7 lies flat upon the web 2, all parts thereof being parallel to the plane of said web.

- 5 A pair of hinges 6 are attached to the cards in any suitable manner. Each hinge may be provided with an eyelet 14 adapted to receive the free end 11 of a hanger. To mount a card 5 upon a hanger 7 one hinge 6 10 is merely disposed adjacent the body portion 8 of the hanger and slid along the length of said body portion until the end 11 is threaded in the eyelet 14. The card is then flexed to temporarily contract it sufficiently to 15 bring the hinge 6 on the other side of the card to a point adjacent the opposite end 11 of hanger 7. The card is then permitted to expand to normal length, the hinge being slid along the body portion until that end 11 20 is threaded in the eyelet 14 of that hinge. In this manner, as can be readily seen, the body 8 serves as a guide for the quick and convenient mounting of a card 5 upon a hanger.
- 25 When the ends 12 and 13 of the hanger have been inserted beneath the flanges of the frame they abut against the adjacent hanger, as shown best at 15 in Fig. 1, and in this way serve to properly space the cards 30 so that the lower marginal edge of each card is exposed to view. This space is preferably employed as an index for the subject matter upon the card.

From the foregoing, it will be seen that 35 since the hangers lie immediately adjacent to the web 2 and parallel thereto, the cards upon the frame 1 will occupy a minimum depth upon the frame. This feature assumes an extremely important aspect, since 40 frames of this type are usually grouped together and mounted in a cabinet, (not shown) the individual frames comprising the drawers of the cabinet. It can readily be seen that for a cabinet of given height, 45 the capacity of the cabinet is dependent upon the depth of the drawers or, as in this case, the thickness or depth of the cards upon each frame. Accordingly, since the hangers 7 are mounted substantially flush 50 with the surface of the web 2 no space upon the frame is wasted, and hence a maximum number of frames may be disposed in a cabinet of a given height.

In using a visible record system embodying my invention, the card desired can be 55 readily ascertained from the visible index at the lower marginal edge and the next succeeding card above it turned upwardly. The separate cards in the system are readily 60 removable for change or replacement and the device is one which possesses a wide range of adjustment in that a plurality of cards may be placed upon the same hanger. Thus, if the data relating to an individual 65 business becomes larger than that of the re-

maining subjects listed, proper expansion can be made without inserting an additional hanger.

I claim as my invention:

1. The combination with a frame having spaced guide flanges, of means for removably attaching a card to said frame, comprising a member having return-bent ends forming spaced bearing portions for insertion beneath said guide flanges and offset continuations of said return-bent portions in the same plane therewith adapted to detachably engage the card. 70

2. The combination with a frame having spaced guide flanges, of means for removably attaching a card to said frame, comprising a member having return-bent ends forming spaced bearing portions for insertion beneath said guide flanges and offset continuations of said return-bent portions in the same plane therewith adapted to detachably engage the card, said offset continuations terminating immediately adjacent the body portion of said member. 80

3. The combination with a frame comprising a flat web having spaced guide flanges on opposite side edges, of means for removably attaching a card to said frame, comprising a member having return-bent ends forming spaced bearing portions for insertion beneath said guide flanges, the return-bent portions lying in a plane adjacent the plane of the web, and offset continuations of said return-bent portions lying in the same plane therewith adapted to detachably engage the card. 90

4. A mounting for detachably holding a card, comprising a wire having return-bent ends terminating in offset continuations adapted to detachably engage a card, said offset continuations being in the same plane with the return-bent portions. 100

5. A mounting for detachably holding a card, comprising a wire having return-bent ends terminating in offset continuations 110 adapted to detachably engage a card, said offset continuations being in the same plane with the return-bent portions and terminating adjacent the wire, the wire serving as a guide for the ready engagement of 115 the cards upon the offset continuations.

6. The combination with a frame having spaced guide flanges, of means for removably attaching a card to said frame comprising a hanger having a main body portion extending between said spaced guide flanges and provided with supporting portions lying in substantially the same plane as and parallel to the main body portion, said supporting portions being adapted to detachably engage the card. 120

7. The combination with a frame having spaced guide flanges, of means for removably attaching a card to said frame comprising a hanger having a main body portion 125

extending transversely across the face of the frame and being contiguous therewith and provided with a card-supporting portion lying in substantially the same plane as and substantially parallel to the main body portion and adjacent the face of the frame, said portion being adapted to detachably engage the card.

8. The combination with a frame comprising a flat web having spaced guide flanges on opposite side edges, of means for removably attaching a card to said frame comprise a hanger having a main body portion extending transversely across the face of the frame between the said guide flanges, the said body portion being contiguous with and in a plane parallel to the face of the web, and provided with a card-supporting portion lying in substantially the same plane as the main body portion and being adjacent to and longitudinally parallel therewith, said portion being adapted to detachably engage the card.

9. The combination with a frame comprising a flat web having spaced guide flanges on opposite side edges, of means for removably attaching a card to said frame comprising a hanger having a main body portion extending transversely across the face of the frame between said guide flanges, the said body portion being contiguous with and in a plane parallel to the face of the web and provided with a card-supporting portion lying in substantially the same plane as the main body portion and parallel to the face of the frame, and adjacent and longitudinally parallel to the said main body portion of the hanger, said portion being adapted to detachably engage the card.

40 In testimony whereof I affix my signature.
FRANK D. POWELL.
